DESIGN FOR A NECKTIE

Albert J. McElfresh, Anderson, Ind.

Application December 15, 1941, Serial No. 104,650

Term of patent 7 years

To all whom it may concern:

Be it known that I, Albert J. McElfresh, a citizen of the United States, residing at 2126 Pearl Street, Apartment Number One, Anderson, in the county of Madison and State of Indiana, have invented a new, original, and ornamental Design for Neckties, of which the following is a specification, reference being had to the accompanying drawing, forming part thereof. The figure is a plan view of a necktie, showing my new design.

I claim:

The ornamental design for a necktie, as shown.

ALBERT J. McELFRESH.
